NECKTIE RACK OR SIMILAR ARTICLE

George Milkie, New York, N.Y., assignor to Charles Fischett, New York, N.Y.

Filed Apr. 9, 1959, Ser. No. 55,421

Term of patent 14 years

(Cl. D33—8)

FIG. 1

FIG. 3

FIG. 1 is a front elevational view illustrating my new design for a necktie rack or similar article.

FIG. 2 is a side elevational view thereof.

FIG. 3 is a top plan view thereof.

I claim:

The ornamental design for a necktie rack or similar article, substantially as shown.
